[57] CLAIM

The ornamental design for a telephone station stand, as shown and described.

DESCRIPTION

FIG. 1 is a top front perspective view of a telephone station stand in accordance with our new design;

FIG. 2 is a top planar view thereof;

FIG. 3 is a side elevation thereof, the opposite side being essentially a mirror image of the side shown;

FIG. 4 is a bottom planar view thereof;

FIG. 5 is a front elevation thereof, the back elevation being essentially a mirror image of the front view shown.

The broken lines representing display digits are shown for illustrative purposes only.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 289,897

DATED : May 19, 1987
